United States Patent Office

Des. 204,646
Patented May 3, 1966

204,646

SEWING MACHINE

George M. Reimer, Elmwood Park, Ill., assignor to Union
Special Machine Company, Chicago, Ill., a corporation
of Illinois

Filed Apr. 17, 1964, Ser. No. 79,563

Term of patent 14 years

(Cl. D70—1)

FIG. 2.

FIG.3.

FIG. 4.

FIG. 5.

FIG. 1 shows a front elevational view of a sewing machine embodying my design;

FIG. 2 is a rear elevational view of said sewing machine;

FIG. 3 is an end elevational view of said sewing machine as seen from the left in FIG. 1;

FIG. 4 is an end elevational view of said sewing machine as seen from the right in FIG. 1; and

FIG. 5 is a top plan view of said sewing machine.

I claim:

The ornamental design for a sewing machine, as shown.
